JOHN TISCHLER, OF EAST PORTCHESTER, CONNECTICUT, ASSIGNOR OF ONE-HALF TO
VICTOR PIVARNIK, OF EAST PORTCHESTER, CONNECTICUT.

CARPENTER'S PLANE.

1,123,957.

Specification of Letters Patent.

Patented Jan. 5, 1915.

Application filed February 7, 1912. Serial No. 675,921.

To all whom it may concern:

Be it known that I, JOHN TISCHLER, a citizen of the United States, and residing at East Portchester, in the county of Fairfield 5 and State of Connecticut, have invented certain new and useful Improvements in Carpenters' Planes, of which the following is a specification, such as will enable those skilled in the art to which it appertains to 10 make and use the same.

This invention relates to carpenters' planes, and particularly to devices of this class designed for use in cutting out mortises in door frames, window frames and the like 15 to receive the butts of hinges, and the object of the invention is to provide an improved device of this class, which may be operated in both directions or by a pushing or a pulling movement, and which is simple in construction and operation; and with this and 20 other objects in view the invention consists in a device of the class specified constructed as hereinafter described and claimed.

The invention is fully disclosed in the 25 following specification of which the accompanying drawing forms a part, in which the separate parts of my invention are designated by suitable reference characters in each of the views, and in which:

30 Figure 1 is a central longitudinal section of a plane of the class specified constructed according to my invention. Fig. 2 a section on the line 2—2 of Fig. 1, and Fig. 3 a section on the line 3—3 of Fig. 1.

35 In the practice of my invention I provide a plane stock a which is of the form in cross section shown in Fig. 3, and comprises a base plate a^2 , and side members a^3 , and the base plate a^2 is provided with a large central opening a^4 at each side of which and at 40 the rear thereof the side members a^3 of the stock are provided with raised ears a^5 . The central aperture a^4 is of sufficient extent in a direction longitudinally of the plane stock 45 to permit the bit of the plane to be projected bodily downward through said aperture for a considerable distance so that it may be employed in planing or cutting the bottom of a recess such as a mortise or hinge 50 recess or the like, while the bottom face of the stock rests upon the surface of the work surrounding said recess.

At a predetermined point rearwardly of the opening a^4 , the base plate a^2 of the stock

is provided with a raised transverse member a^6 having a downwardly and forwardly inclined top surface on which is placed the bit b of the plane, and rearwardly of the member a^6 , said base plate of the stock is also provided with another raised member a^7 60 having a downwardly and forwardly inclined top surface, in which is a forwardly and backwardly ranging groove a^8 in which is mounted a yoke-shaped block c the side portions c^2 of which are provided at the top 65 thereof with teeth c^3 adapted to enter transverse grooves b^2 in the bit b . I also provide a screw d which is passed forwardly through the transverse raised member a^6 , and the rear end portion d^2 of which is cylindrical 70 in form, and provided adjacent to the screw portion with a reduced portion d^3 forming annular shoulders d^4 and d^5 , and the reduced portion d^3 fits in the yoke-shaped block c , and said screw is provided with a head d^6 75 and by turning said screw by means of said head the bit b may be adjusted forwardly and backwardly as will be readily understood, and according to the direction in which said screw is turned. It will be observed that the forward and backward movement of the screw d is occasioned by its being turned in the part a^8 which is threaded to correspond with the thread on said screw, and that, that part of said screw in the 80 block c is not threaded, the movement of said block being occasioned by the annular shoulders d^4 and d^5 .

Mounted transversely in the ears a^5 above and rearwardly of the opening a^4 , in the 90 base plate a^2 of the stock, is a pin e , and I also provide a lock handle lever f having an enlarged rear end portion f^2 which forms a handle, and a forwardly directed wedge-shaped portion f^3 which passes between the 95 bit b and the pin e , and said part f^3 is provided in the top thereof with a recess f^4 in which the pin e fits, and passed downwardly through the handle lock lever f is a screw g which bears on the bit b directly 100 over the transverse raised portion a^6 and which is provided with a milled head g^2 .

By turning the screw g in one direction the front end of the wedge shaped portion f^3 of the handle lock lever f will be pressed 105 onto the bit b at h , and this forms of said lever a clamp lock for said bit of which the screw g forms a part as will be readily

understood, and by means of which the said bit may be securely locked in any desired position of adjustment; and whenever it is desired to adjust said bit the screw *g* 5 is loosened and the screw *d* turned in the desired direction after which the screw *g* is again tightened, and said bit may be entirely removed for any purpose by loosening said screw *g* and pulling said bit out- 10 wardly and backwardly.

The stock *a* is also provided at the front end portion thereof with a handle *i*, and in the operation of the device the handle *i* is grasped in one hand and the head *f*² of the 15 handle lock lever *f* in the other, and the device may be moved forwardly, or forwardly and upwardly, and backwardly, or backwardly and downwardly, according to the position of the work-piece or the frame, 20 or other article in which it is desired to form a mortise to receive a hinge butt.

As will be observed the plane stock extends a considerable distance both forward and back of the opening *a*⁴ which is substantially in the center of the plane stock, 25 and it will be obvious that the bit can be adjusted so as to cause it to extend through said opening and project to a considerable distance below the face of the plane stock 30 to permit the plane to be used in forming mortises and other recesses, the plane bit being gradually adjusted downwardly and the plane being operated first in one direction and then in another during the formation 35 of such mortises or recesses, so that the bit will cut to the opposite ends of the same, while the bottom face of the plane stock is supported upon the surface of the work on opposite sides of the recess which is being 40 formed. In this respect my improved plane differs from planes as usually constructed in which it is not possible to project more than a small portion of the bit adjacent to the cutting edge through the opening in the 45 bottom of the plane stock and in which the said opening is located much nearer to one end of the plane stock than the other, thus precluding its use for the formation of mortises and other recesses. As indicated in 50 Figs. 2 and 3 of the drawings both the plane stock and the plane bit may be made quite narrow so that mortises and recesses such as are ordinarily desired in connection with woodworking can be readily formed thereby. 55 It will be noted that in my improved construction the adjusting screw *d* is provided

with supports in the nature of bearings at different points longitudinally thereof. The threaded end of the screw finds a bearing in the threaded aperture in the boss *a*⁶ and 60 a further bearing is provided by the yoke *c*, which rests upon the boss *a*⁷. This construction precludes the screw from being deflect- 65 ed in such a manner as to bend it or make it bind in its threaded bearing aperture. It will also be noted that the bit is supported at three points in its length, to wit, at the edge of the aperture *a*⁴, on the boss *a*⁶, and on the yoke *c*, and that the screw *g*² which 70 engages the bit substantially centrally of its length is directly over the boss, so that no matter how tightly the bit is clamped neither the bit nor the adjusting screw are bent or deflected from their normal position.

Having fully described my invention what 75 I claim as new and desire to secure by Letters Patent is:—

In a carpenter's plane, the combination with the main body having a bit aperture in the bottom thereof, and a beveled bit supporting face adjacent to the rear edge of said aperture, said main body being also provided with an integral boss in rear and at a distance from said aperture, having a threaded aperture therein, and with a sec- 80 ond boss in rear of and at a distance from the first mentioned boss, of a yoke having a sliding engagement with said second boss and resting thereon, said yoke being pro- 85 vided with means for engaging the bit to move it longitudinally, an adjusting screw engaging the threaded opening in the first mentioned boss and having portions engag- 90 ing said yoke, a bit supported upon said bit engaging face, said first mentioned boss 95 and said yoke, and being thus supported at three longitudinally separated points, a lock lever above said bit provided with a set screw for engaging the bit above said first mentioned boss, and means connected with 100 said main body for engaging the said lever on its upper side adjacent to the bit aperture whereby the bit adjusting mechanism is relieved from strain and pressure.

In testimony that I claim the foregoing 105 as my invention I have signed my name in presence of the subscribing witnesses this 6th day of February, 1912.

JOHN TISCHLER.
